UNITED STATES PATENT OFFICE.

GEORGE B. BASSETT, OF BUFFALO, NEW YORK.

DESIGN FOR A WATER-METER CASE.

SPECIFICATION forming part of Design No. 27,697, dated September 28, 1897.

Application filed July 14, 1897. Serial No. 644,580. Term of patent 14 years.

To all whom it may concern:

Be it known that I, GEORGE B. BASSETT, a citizen of the United States, residing at Buffalo, in the county of Erie and State of New York, have invented and produced a new and original Design for Water-Meter Cases, of which the following is a specification, reference being had to the accompanying drawings, forming a part thereof.

Figure 1 is a top plan view of a case which embodies my new design. Fig. 2 is an end elevation of the case shown in Fig. 1.

As shown in the drawings, the leading or material feature of my design consists of the case with a substantially circular body and with meeting flanges having two straight and parallel side edges and four corners, in each of which is located a flange-bolt.

A is the upper part of the meter-case, which has the flange B formed on its meeting edge with two straight parallel sides. A' is the lower part of the meter-case, which has the flange B' formed on its meeting edge with two straight parallel sides. In the four corners of the meeting flanges at C are located the four bolts D.

Having described my invention, what I claim as new, and desire to secure by Letters Patent, is—

The design for a water-meter case substantially as herein shown and described.

GEORGE B. BASSETT.
